UNITED STATES PATENT OFFICE.

ALFRED S. HENN, OF NEW HAVEN, CONNECTICUT.

SNAP-HOOK.

SPECIFICATION forming part of Letters Patent No. 229,885, dated July 13, 1880.

Application filed April 21, 1880. (No model.)

To all whom it may concern:

Be it known that I, ALFRED S. HENN, of New Haven, in the county of New Haven and State of Connecticut, have invented a new and 5 useful Improvement in Snap-Hooks, of which the following is a specification.

My invention relates to snap-hooks; and the improvements consist in making the front ends of both body and tongue curved and overlapping each other, and so that a cross-section 10 of the overlapping ends shall approach a semicircle in form; also, in making a transverse semicircular and curved groove in both the body and tongue to inclose the springs, as hereinafter more fully set forth and claimed.

In the drawings, which I hereby make a part 15 of the specification, Figure 1 is a view of the hook, partly in section, showing the space occupied by the spring. Fig. 2 is a view of the body, and Fig. 3 a view of the tongue of the hook, reversed in respect to the body, as shown 20 in Fig. 2. Fig. 4 is a cross section in the direction of the broken line xx in Fig. 1, showing the spring in position.

To enable others to make and use my improved hook, I will describe it in detail.

The body A has its front end made in the form shown in Fig. 1. Near the loop a transverse curved and semicircular groove, a , is 25 formed, extending nearly across the hook. At the end of the groove the rest m is formed and projects, the projection being semicircular in form to fit into the groove in the tongue.

The tongue B has its front end made as

shown in Fig. 3, and is fastened to the body 35 by a screw or rivet, on which it turns. A transverse curved and semicircular groove, b , is formed on its end, and extends nearly across the tongue. At the end of the groove the rest n is formed and projects, the projection being 40 semicircular in form to fit the groove in the body of the hook.

The spiral spring C is inclosed in the grooves in the body and tongue, one end coming against the rest m and the other against the rest n . 45

Having described my invention, what I claim as new, and desire to secure by Letters Patent, is—

The improved snap-hook herein described, consisting, essentially, of the body A, having 50 its front end overlapping the front end of the tongue, also having the transverse semicircular and curved groove a , made in a plane parallel with the plane of the loop and rest m , of the tongue B, having its front end overlapping the front end of the body of the hook, 55 also having the transverse semicircular and curved groove b , made in a plane parallel with the plane of the loop and rest n , and of the spiral spring C, inclosed in the grooves a and b between the rests m and n , and arranged in the same plane with the loop, the front overlapping ends being formed as shown, substantially as set forth.

ALFRED S. HENN.
